ABSTRACT: A reference tone signal is recorded in a specific channel of a multiple-channel recorder-reproducer incorporated within an electronic musical instrument simultaneously with recording of music played on the instrument. During reproduction, this reference signal is also reproduced and automatically compared with the corresponding tone signal directly from a tone generator of the instrument to produce a comparison output, which is used to accomplish automatic equalization of the pitches of the music being reproduced and those of the corresponding tones of the tone generators of the instrument.

AUTOMATIC SYNCHRONIZATION OF PITCHES IN ELECTRONIC MUSICAL INSTRUMENTS WITH MAGNETIC RECORDING-REPRODUCING APPARATUS

BACKGROUND OF THE INVENTION

This invention relates generally to electronic musical instruments and magnetic sound recording and reproducing apparatuses (hereinafter referred to as "recorder-reproducers") and more particularly to electronic musical instruments having recorder-reproducers incorporated therein in a built-in manner.

More specifically, the invention concerns automatic equalization or synchronization of pitches in electronic musical instruments of the above stated character, that is, automatic synchronization whereby aberrations or deviations of pitches of reproduced tones due to causes such as elongation of the recording tape at the time of reproduction and fluctuation in the speed of the tape drive motor are compensated for to cause the pitch of each reproduced tone and the pitch of the corresponding tone produced by a tone generator of the musical instrument to be equal.

In instances such as that when a recorder-reproducer is used in combination with an electronic musical instrument, and music generated by the electronic musical instrument is recorded on a recording tape and is subsequently reproduced therefrom, or when a previously recorded tape is used to reproduce music recorded thereon for purposes such as practice in playing the electronic musical instrument, the pitches of the reproduced tones tend to deviate from the pitches of the corresponding tones produced by the tone generators of the instrument.

This pitch deviation is due to causes such as deformation of the recording tape, fluctuation of the speed of the tape drive motor, and fluctuation of the tone generator of the electronic musical instrument itself. Consequently, when the musical instrument is played simultaneously with reproduction of a recorded musical composition, unmusical or discordant superimposed tones and chords tend to be produced. This pitch deviation has heretofore been a major difficulty accompanying electronic musical instruments with built-in recorder-reproducers.

SUMMARY OF THE INVENTION

It is an object of the invention to overcome the above described difficulty by providing, in an instrument of the above stated character, means for automatically synchronizing or equalizing the pitch of each musical tone recorded and reproduced and the pitch of the tone produced by the corresponding tone generator of the instrument.

According to the present invention, in one aspect thereof, the above mentioned synchronizing means accomplished the operation of simultaneously recording musical tone signals and one signal within the same tone generator as a reference signal at the time of recording, comparing this reference signal at the time of reproduction with the corresponding tone generator signal of the instrument at the time of reproduction to produce a comparison output, and apply this output to the motive power means of the recorder reproducer thereby to control the speed thereof and to obtain reproduced tone signals of the same pitches as the corresponding pitches of the musical instrument played at the time of reproduction.

According to the present invention, in another form thereof, the above mentioned comparison output is applied to the main oscillator of the tone generators thereby to obtain the desired equalization of pitches.

The nature, principles, details, and utility of the invention will be more clearly apparent from the following detailed description with respect to preferred embodiments of the invention, when read in conjunction with the accompanying drawing, in which like parts are designated by like reference numerals.

BRIEF DESCRIPTION OF THE DRAWING

In the drawing:

FIG. 1 is a block diagram showing the essential organization of an example of an electronic musical instrument provided with a recorder-reproducer and one example of an automatic pitch synchronizing system according to the invention; and

FIG. 2 is a similar block diagram showing another example of embodiment of the invention.

DETAILED DESCRIPTION

Referring to FIG. 1, the part of conventional organization of the electronic musical instrument shown therein comprises, in sequence, tone generators 1, switches 2 operable by keys 3, filter circuits 4, tone volume controls 5, an amplifier 6, an expression control 7, a power amplifier circuit 8, and a loudspeaker 9.

In the example of the invention shown in FIG. 1, there is provided a recorder-reproducer 10 which is capable of recording simultaneously multichannel signals and reproducing the same and has a recording input terminal 10b and a reproducing output terminal 10ba corresponding to a specific track or channel and a recording input terminal 10a and a reproducing output terminal 10aa corresponding to a channel other than the first mentioned specific channel.

The recording input terminal 10a is connectable through a fixed contact 11f (recording) and movable contact 11m of a record-reproduce switch 11 to the junction between the expression control 7 and the power amplifier 8. The reproducing output terminal 10aa is connected to the other (reproducing) fixed contact 11fa of the switch 11. Thus, when the electronic musical instrument is played, the musical tone signals thus rendered can be recorded and subsequently reproduced by the recorder-reproducer 10.

On the other hand, the recording input terminal 10b corresponding to the aforementioned specific channel is connectable through a fixed contact 12f (recording) and movable contact 12m of a switch 12 to a terminal 1a let out from a particular part of the tone generator circuit 1. Thus, when recording is carried out, a particular signal from the tone generator circuit is always recorded in the above mentioned specific channel.

In the instant example, there is further provided a detector circuit 14 having two input terminals 14a and 14aa and being operable by two signals respectively supplied through these input terminals. The detector 14 thereupon operates to put out an ambipolar DC voltage or current output proportional to the frequency difference of the two input signals, that is, a reference standard frequency minus the detected frequency, through an output terminal 14b.

One input terminal 14aa of the detector 14 is connectable through the movable contact 13m and fixed contacts 13f and 13fa of a switch 13 in a freely selectable manner to the input terminal 10b and output terminal 10ba of the recorder-reproducer 10. The other input terminal 14a of the detector 14 is connected to the aforementioned terminal 1a of the tone generator circuit 1. The output terminal 14b is connected through a suitable power amplifier circuit 15 to an input terminal 10c of the driving mechanism of the recorder-reproducer 10 together with a power supply 16 for the driving mechanism with a superimposed relationship thereto.

Although not absolutely necessary it is preferable that the above described switches 11, 12, and 13 be in mutually intercoupled or ganged relationship.

The example of the above described organization according to the invention operates in the following manner. First, the case where in a recording is to be made in the recorder-reproducer will be considered.

In this case, movable contacts 11m, 12m, and 13m of switches 11, 12, and 13 are moved to the sides of their respective fixed contacts 11f, 12f, and 13f. Accordingly, each musical signal is recorded in a channel other than the aforementioned specific channel. Simultaneously, a single signal among the signals generated in tone generator circuit 1, for example, $A_4 = 440$ Hz, is obtained as a reference standard signal from terminal 1a and is recorded in the specific channel. It is to be

observed that this signal is used as a control signal for controlling the reproducing speed of the recorder-reproducer at the time of reproduction as will become apparent as the description proceeds.

In this case, since the same signal $A_4 = 440$ Hz is being supplied to both of the two input terminals $14a$ and $14aa$ of detector 14, the frequency difference thereof is zero. Accordingly, the output at output terminal $14b$ of the detector is also zero, and the driving motor (not shown) of recorder-reproducer 10 is driven by only power supply 16 for driving, no power whatsoever being supplied from power amplifier 15.

For reproduction, on the other hand, movable contacts $11m$, $12m$ and $13m$ of switches 11, 12, and 13 are moved to the sides of their fixed contacts $11fa$, $12fa$, and $13fa$, whereupon each recorded musical signal is reproduced by recorder-reproducer 10, amplified by power amplifier 8, and radiated as sound from loudspeaker 9. At the same time, the reference signal $A_4 = 440$ Hz recorder in the specific channel is also reproduced.

However, if at this time there is a pitch deviation due to causes such as deformation in the recording tape, fluctuation in the rotational speed of the tape drive motor, and fluctuation in the tone generators of the electronic musical instrument, the two signals applied to detector 14 as described above differ from those at the time of recording.

For example, in the case when a stretching of the recording tape occurs, the signal from the tone generator circuit 1 corresponding to the recorded control signal has a frequency $A_4 = 440$ Hz, but the reproduced signal from the above mentioned specific channel, i.e., the reproducing speed control signal, acquires a frequency which is lowered by the stretching of the tape. If, for example, this frequency is lowered to 435 Hz, the frequency difference between the tone generator signal and the reproduced speed control signal (detected signal) will become +5 Hz.

Accordingly, an output proportional to this frequency difference will be obtained at output terminal $14b$ of detector 14. This output will then be amplified by power amplifier 15 and, being superimposed on the output of power supply 16, will be supplied to the motor for driving recorder-reproducer 10. Thus, the power supplied to this motor will increase, whereby the motor speed will increase to increase the reproducing speed, and a musical reproduced signal of the correct pitch will be obtained.

Furthermore, in the case of pitch deviation due to a cause such as fluctuation in the tone generator circuit of the musical instrument as described above, wherein the frequency of the tone generator fluctuates to 435 Hz, for example, the frequency difference between this frequency and the reproduced speed control signal will become -5 Hz.

Accordingly, an output proportional to this frequency difference will be obtained at output terminal $14b$ of detector 14. This output will then be amplified by power amplifier 15 and be superimposed on the output of power supply 16. In this case, however, since the output of detector 14 is of negative polarity, the power supplied to the drive motor of recorder-reproducer 10 will decrease, whereby the motor speed will be reduced, and control will be accomplished to equalize the pitch of the musical instrument and that of the musical reproduced signal.

In another example of practical embodiment of the invention as illustrated in FIG. 2, the known organization of the electronic musical instrument proper comprising tone generators 1, switches 2 operable by keys 3, filter circuits 4, tone volume controls 5, an amplifier 6, an expression control 7, a power amplifier 8, and a loudspeaker 9 is similar to that of the example described hereinabove with reference to FIG. 1.

Furthermore, a multichannel recorder-reproducer 10 of magnetic type capable of simultaneous recording and reproducing multichannel signals and a comparison detection circuit or detector 14 are also connected to the musical instrument proper in a manner similar to that in the example shown in FIG. 1 except that the output terminal $14b$ of the detector

14 is connected to a frequency control terminal $1b$ of a main oscillator within the tone generator circuit 1 thereby to control the oscillation frequency thereof. The detector gives out a control signal proportional to the frequency difference of the detected frequency minus the main oscillator frequency.

The components of the circuit including switches 11, 12, and 13 and their connections are the same as those in the example shown in FIG. 1.

For recording, movable contacts $11m$, $12m$, and $13m$ of the three switches are moved to engage respectively fixed contacts $11f$, $12f$, and $13f$, whereupon each musical tone signal which has passed through expression control 7 is supplied through movable contact $11m$ and fixed contact $11f$ and through input terminal $10a$ to recorder-reproducer 10 to be recorded in a channel other than the aforementioned specific channel.

At the same time, one signal from among the tone generator signals generated and transmitted through output terminal $1a$ of tone generators 1, for example, a signal $A_4 = 440$ Hz, is led out as a reference standard signal. This signal is supplied by way of movable contact $12m$ and fixed contact $12f$ and through input terminal $10b$ to recorder-reproducer 10 to be recorded in the above mentioned specific channel.

In this case, since the two input signals with respect to the detector are both signals of $A_4 = 440$ Hz, the frequency difference is zero, and, therefore, the detector output is also zero. Accordingly, since no signal whatsoever is supplied to the main oscillator of the tone generators 1, there is no variation in the oscillation frequency.

For reproducing, switches 11, 12, and 13 are changed over by placing movable contacts $11m$, $12m$ and $13m$ in contact with fixed contacts $11fa$, $12fa$, and $13fa$. Each musical tone signal recorded in recorder-reproducer 10 is reproduced and, passing through fixed contact $11fa$ and movable contact $11m$ of switch 11, is power amplified by power amplifier 8 and radiated as sound from loudspeaker 9. Simultaneously, the reference standard signal $A_4 = 440$ Hz of tone generators 1 recorded in the specific channel is also reproduced.

However, if at this time there is a pitch deviation due to any of the aforementioned causes, the two signals applied to detector 14 will differ from those at the time of recording. For example, in the case when a stretch occurs in the recording tape, the signal from the tone generators is $A_4 = 440$ Hz, and if the signal reproduced from the recorder-reproducer becomes of a frequency of 435 Hz, for example, because of the stretch in the tape, the frequency difference between the detected signal and the tone generator signal will become -5 Hz.

Consequently, the output of detector 14 will become proportional to this frequency difference. This output is then applied to the main oscillator of tone generators 1 to effect control whereby the oscillation frequency thereof is reduced, thereby operating to cause the reproduced musical tone signal from the recorder-reproducer and the signal of the tone generator of the electronic musical instrument to become equal in pitch.

Furthermore, in the case wherein the pitch of a tone generator of the musical instrument deviates from the standard pitch, resulting with the detector input from the tone generator being at a frequency of 435 Hz, and the reproduced reference signal from the recorder-reproducer is normally of a frequency of 440 Hz, for example, the frequency difference between the reproduced reference signal and the tone generator signal will be +5 Hz. Since the output of detector 14 is proportional to this difference, a signal such as to raise the oscillation frequency is applied to the main oscillator of the tone generators 1, whereby the pitch of the musical tone reproduced signal of recorder-reproducer 10 and the pitch of the tone generator of the musical instrument are caused to be equal.

In the first described example of the invention, the operation comprises, essentially, recording simultaneously musical tone signals and one signal within the same tone generator as a reference signal at the time of recording, comparing this

reference signal at the time of reproduction with the corresponding tone generator signal of the electronic musical instrument, and applying the resulting comparison output to the driving motor of the recorder-reproducer thereby to obtain musical tone signal of the same pitches as the corresponding pitches of the musical instrument played at the time of reproduction.

In the second example of the invention, the operation comprises, essentially, recording simultaneously a musical tone signal and one signal within the same tone generator as a reference signal at the time of recording, comparing this signal with the corresponding tone generator signal of the musical instrument at the time of reproduction, and applying the resulting comparison output to the main oscillator of the tone generators thereby to cause the pitch of each reproduced musical tone signal and the pitch of the corresponding tone of the electronic musical instrument to be equal.

Thus, an electronic musical instrument provided with an incorporated sound recording and reproducing apparatus and with the pitch synchronizing system of the invention is capable of rendering superimposed tones and chords in an extremely beautiful manner in instances such as, for example, that of a duet rendered by playing the musical instrument in concert with a reproduced musical composition or that wherein use is made of a recording tape with sound recorded thereon for purposes such as practice in playing the electronic musical instrument.

While, in each of the above described examples of the invention, a tone generator tone signal of the electronic musical instrument itself is used as a reference signal, it will be apparent that a separate signal source can also be used.

It should be understood, of course, that the foregoing disclosure relates to only preferred embodiments of the invention and that it is intended to cover all changes and modifications of the examples of the invention herein chosen for the purposes of the disclosure, which do not constitute departures from the spirit and scope of the invention as set forth in the appended claims.

I claim:

1. In an electronic musical instrument having tone genera-

tors, a loudspeaker, and a magnetic sound recording and reproducing apparatus driven by motive power means and incorporated within the instrument for recording and reproducing musical tone signals played thereon, an automatic pitch synchronizing system comprising, in combination:

means for recording and reproducing a reference signal simultaneously with and separate from said musical tone signals;

detection means for comparing, during reproduction, the reference signal thus reproduced with a respective signal directly from the corresponding tone generator to produce a comparison signal which is a function of the difference between the signals thus compared; and

control means operating in response to said comparison signal to equalize, during reproduction, the pitches of the reproduced musical tone signals and the pitches of corresponding tones played on the instrument during said reproduction.

2. The automatic pitch synchronizing system as claimed in claim 1 in which the control means operates in response to the comparison signal to control said motive power means thereby to control the reproduction speed of the recording and reproducing apparatus.

3. The automatic pitch synchronizing system as claimed in claim 1 which further comprises a main oscillator of variable frequency for the tone generators, and in which the control means operates in response to the comparison signal to control the oscillation frequency of said main oscillator.

4. The automatic pitch synchronizing system as claimed in claim 1 in which the detection means is a detector circuit having an input terminal connected to an output terminal of the tone generators, and the means for recording and reproducing a reference signal comprises the magnetic sound recording and reproducing apparatus, which is of multiple channel type having a specific channel for recording the reference signal, and switching means for directing the reference signal from a tone generator directly as input to said specific channel during recording and for directing the recorded reference signal from the specific channel to another input terminal of the detector circuit during reproduction.
